W. DOYLE.

Cooking Stove.

No. 78,517.

Patented June 2, 1868.

United States Patent Office.

WILLIAM DOYLE, OF ALBANY, NEW YORK.

Letters Patent No. 78,517, dated June 2, 1868.

IMPROVEMENT IN COOKING-STOVES.

The Schedule referred to in these Letters Patent and making part of the same.

TO ALL WHOM IT MAY CONCERN:

Be it known that I, WILLIAM DOYLE, of the city of Albany, in the county of Albany, and State of New York, have invented a new and improved Cooking-Stove; and I do hereby declare that the following is a full, clear, and exact description thereof; reference being had to the accompanying drawings, making a part of this specification, in which—

Figure 1 is a perspective view of my invention, with the front, top, side, and oven-plates left out, so as to show better the arrangement of the flues in the stove.

Figure 2 is a vertical central section of stove.

Figure 3 is a horizontal section through bottom flues of stoves.

Figure 4 is a perspective view of flue-stopper B' and extension-flue C.

Figure 5 is a view of another form of flue C.

The principal object of my invention is so to construct a cooking-stove that a more uniform distribution of heat may be given to all parts of the oven, the front as well as the top, back, and bottom of the same, as will be hereinafter described.

Another object of my invention is to provide a better boiling and broiling arrangement in cooking-stoves, and also, by an equable distribution of the draught from the fire, to insure a more perfect combustion of the fuel, and also greater economy in the use of the same, as will be hereinafter described.

Another object of my invention is so to arrange a descending front-flue, and to combine it with the direct portion of a return or revertible flue in the bottom of a cooking-stove, that the whole may be controlled and operated by one damper, as will be hereinafter described.

To enable others skilled in the art to understand my invention, I will describe its construction and operation.

In the accompanying drawings, A represents a flue in the front of the stove, and formed between the fire-box D and front plate U, and extending from side to side of the stove, as shown in fig. 1. This flue may be made to occupy only the two front corners of the stove, as shown by curved lines, g g, in fig. 1, and all that portion of the flue extending across the front of the stove, from corner flues g g, may be made simply an air-chamber; but I prefer to have it all one flue, and open at the top, from end to end of the fire-box, as shown in fig. 1.

Below the fire-box D, flue A is divided into two portions, and carried down the two front corners of the stove to the ash-plate M, as shown at X, in fig. 2. Below ash-plate M the two corner flues, A A, reunite, and form cross-flue or chamber, H, as shown in fig. 3. Flue or chamber H is formed on one side by the front oven-plate B, and on the other by the front plate U, its top by part of ash-plate M, and its bottom by the bottom of the stove; it has a flue-stopper, N, made in the usual manner, all as shown in figs. 2 and 3.

Within chamber or flue H, and through front oven-plate B, I provide a flue-stopper, B', shown in fig. 4, having flue-plates a attached to it. Said plates a are united at their top edges, and wide apart at their bottoms forming a triangular-shaped extension-flue, C, as shown in figs. 1, 3, and 4.

Said extension-flue C projects about six inches from front oven-plate B into the direct portion of revertible flue F, and a little beyond the front ends of flue-strips O, in the bottom of the stove, as shown in fig. 3. Flue C may be made square, as shown in fig. 5, having additional flue-strips, b, placed above flue-strips a, to continue and connect the same to the bottom oven-plate, or flue C may be extended nearly to the back of the stove; but I prefer the form shown in fig. 4.

Thus it will be seen that the products of combustion may pass from the front of the fire-box, down flues A to ash-plate M, where they reunite within chamber or cross-flue H, thence they will be conducted, by extension-flue C, into the direct-draught flue F, and thence to outlet K, at the top and back part of the stove, in the usual manner.

It will be seen from the above that the operation of my invention will be as follows:

The fire is started upon the grate in the usual manner, and fuel supplied through the front holes in the top

of the stove, the damper P being turned down, so as to allow the fire to kindle quickly. When the fuel is well ignited, damper P is turned up or closed, as shown in fig. 1, when the draught or current of heated air, and the products of combustion, will pass from the front and the back of the fire-box, as shown by the arrows in figs. 1 and 2. Those on the front of the stove show how the heat is carried down the front of the stove, heating the front oven-plate B, and entering the bottom of the stove, as shown in fig. 3, forming a continuous front descending and direct draught. And the arrows, passing over the top oven-plate, and down the back of the stove, and under the oven into flue F, and thence upwards into exit-flue K, show how the heat and the products of combustion are carried over the top, down the back, and under the bottom of the oven, in a common three-flue stove.

By my invention, the centre of the fire, which is immediately under the vessel to be heated, as shown in fig. 2, is clearer, and therefore hotter than it otherwise would be, and it is better, not only for boiling, but also for broiling, and all other culinary purposes.

By this arrangement and construction of a stove, I am enabled to obtain a more perfect combustion of the fuel than in ordinary stoves, and there being less waste produced in consequence of this better combustion, it is evident that it will also give greater economy.

There is also produced by my invention a more equable distribution of heat through the oven, which is very desirable in this class of stoves.

I do not claim in a cooking-stove causing the products of combustion to pass from both sides of the fire-box, nor do I claim a front descending flue.

Having described my invention, what I claim as now; and desire to secure by Letters Patent, is—

1. The construction and arrangement of extension-flue C, in combination with a revertible or return-flue, F, under the oven of a cooking-stove, substantially as shown and described.

2. Flue-stopper B', in combination with flue-plates *a* of extension-flue C, when constructed as and for the purpose set forth.

3. The construction and arrangement of front descending flues A A, in combination with extension-flue C, substantially as set forth.

4. The arrangement and combination of front descending flues A A, cross or connecting-flue H, extension-flue C, and revertible flue F, substantially as shown and described.

5. The construction and arrangement of a front descending and direct flue or flues, A A, and cross-flue H, united by extension-flue C with a revertible flue, F, under the oven of a cooking-stove, when all of said flues are operated and controlled by one damper, P, substantially as set forth.

WM. DOYLE.
